[57] CLAIM

The ornamental design for a motor controlling relay, as shown and described.

DESCRIPTION

FIG. 1 is a front elevational view of a motor controlling relay showing our new design;
FIG. 2 is a side elevational view thereof;
FIG. 3 is a top plan view thereof;
FIG. 4 is a bottom plan view thereof;
FIG. 5 is a rear elevational view thereof;
FIG. 6 is a side elevational view thereof;
FIG. 7 is a perspective view thereof on an enlarged scale.
